SHEET FEEDING MACHINE

Simon Gaynor, Philadelphia, Pa., assignor to
 American Business Systems, a copartnership
 consisting of Robert Weinstock and Simon Gay-
 nor, Philadelphia, Pa.

Application May 20, 1948, Serial No. 28,160

18 Claims. (Cl. 271—8)

1

The invention relates to improvements in sheet feeding machines and, more particularly, to a machine for feeding single or manifold sheets from a stack into a typewriter or other business machine.

Sheet feeding machines of the general character of the machine of the present disclosure utilize means to advance the stack of sheets progressively as sheets are successively withdrawn so as to locate the foremost sheet in the stack in a position for engagement by sheet feeding mechanisms. Machines of that character are fully disclosed in the pending applications of Fred Schwarzer, Serial No. 698,001, filed September 19, 1946, and Serial No. 732,212, filed March 4, 1947, which applications are owned by the assignee of the instant application.

The instant machine is characterized by the inclusion of novel sheet-picker mechanism, which operates to engage and withdraw the foremost sheet from a stationary stack of sheets irrespective of the number of sheets in the stack within the capacity of the machine; and it is, therefore, an object of the invention to provide such a sheet-picker mechanism.

Another object is to provide, in a sheet feeding machine, a novel association of parts, operating in a single operating cycle, to penetrate and grip a sheet and carry said sheet from a stack into a position of discharge, where the sheet is positively released automatically.

Another object is to provide a novelly constructed automatic sheet penetrating and gripping mechanism initially actuatable to grip and subsequently actuatable to release the sheet upon reaching the limits of its operative movement.

Another object is to provide, in a sheet feeding machine, a hopper or rack for a stack of sheets with extensible means adjustable to accommodate sheets of a size greater than the size of the hopper.

Another object is to provide, in a sheet feeding machine, an easily actuated, simply constructed sheet gripping and feeding mechanism.

Another object is to provide a sheet feeding machine with sheet gripping and feeding mechanism which is wholly concealed from view when in normal ineffective position and, consequently, is less likely to become misadjusted or damaged.

Another object is to provide a sheet gripping and feeding mechanism for a sheet feeding machine which embodies a minimum of parts and is easily and quickly adjusted to adapt the machine for handling single or manifold sheets.

Other and further objects of the present invention will be apparent from the following descrip-

2

tion and claims, and are illustrated in the accompanying drawings which, by way of illustration, show an exemplary embodiment and the principles thereof. Other embodiments of the invention embodying the same principle may be used, and structural changes may be made as desired by those skilled in the art, without departing from the present invention and the purview of the appended claims.

10 In the drawings:

Fig. 1 is a side elevational view of a sheet feeding machine embodying the features of the present invention, showing it attached to a support.

Fig. 2 is a plan view of the machine.

15 Fig. 3 is a front elevational view of the machine as viewed along line 3—3 of Fig. 1.

Fig. 4 is a rear elevational view of the machine as viewed along line 4—4 of Fig. 1.

20 Fig. 5 is an enlarged vertical transverse sectional view of the sheet feeding machine showing parts in elevation, and omitting the standard.

Fig. 6 is a fragmentary detail plan view of the sheet gripping mechanism, taken substantially in the plane of line 6—6 of Fig. 5.

25 Fig. 7 is a transverse sectional view of the sheet gripping mechanism, taken substantially along line 7—7 of Fig. 6, showing parts in section.

Fig. 8 is an elevational view of the rear end of the mechanism shown in Fig. 6, taken substantially along line 8—8 of Fig. 6.

30 Fig. 9 is an elevational view of the front end of the sheet gripping mechanism, taken substantially along line 9—9 of Fig. 6.

Fig. 10 is an inverted plan view of the sheet gripping mechanism taken substantially along line 10—10 of Fig. 8.

Fig. 11 is an elevational view of the actuating plunger and mounting, as viewed in the direction of the arrows 11—11 of Fig. 5.

40 Fig. 12 is a top plan view of the mounting shown in Fig. 11.

Fig. 13 is a side elevational view of the plunger and mounting, viewed in the direction of the arrows 13—13 on Fig. 12.

45 Referring to the disclosure in the accompanying drawings, the sheet feeding machine embodying the features of the present invention preferably is mounted upon a suitable support 11, which may be a typewriter table or the like, by means of a standard generally indicated at 12.

The standard 12 preferably consists of two parts 13 and 14 telescopically associated and secured in an adjusted position relative to each other as by means of a thumb bolt 15 operative to tightly clamp the telescoped end portion of the standard

55

part 13 about the telescoped end portion of the standard part 14. The lower extremity of the standard part 13 is suitably pivoted, as at 16, to a clamp bracket 17, including a tightening screw 18, by means of which the standard is firmly secured to the support 11. The free end of the standard part 14 carries a bracket or frame 19 which is adjustably secured thereto as by means of a tightening screw 21 so as to be firmly secured in any position of angular adjustment.

As best shown in Fig. 5, the bracket 19 preferably is cast, and it includes a hub 22 having a leg or arm 23 extending from one side thereof and provided on its upper face with a pair of transversely projecting lugs 24. An upwardly projecting arm 25 of said bracket 19 likewise has a pair of transversely extending lugs 26 adjacent its uppermost end. These lugs are disposed in a plane substantially at right angles to the plane of the lugs 24, thereby constituting a seat for supporting an open-faced hopper, generally indicated at 27.

The hopper 27 preferably is constructed of sheet material, and it includes a back wall 28 and an integral bottom wall 29 disposed at right angles to the back wall 28. The bottom wall 29 is seated on and suitably secured to the transversely projecting lugs 24 of the bracket 19. The back wall 28 is provided on its outwardly disposed or rear face with a vertical channel 31, across which a mounting plate 32 is firmly secured as by welding. The mounting plate is secured, as by means of mounting screws 33, to the transverse lugs 26 on the bracket arm 25. It should be quite evident, therefore, that the hopper is firmly secured to the bracket 19 and may be adjustably secured in any position best suited for use. As illustrated, the hopper preferably is positioned inclined rearwardly from a substantially vertical plane for purposes to be best understood as the description proceeds.

Mounted within the hopper 27 is a pair of transversely adjustable side walls 34, each of which consists of a flat plate having a flange 35 on one edge thereof. An adjusting screw 36 is threaded into each flange 35 for mounting the plates for adjustment along respective slots 37 in the back wall 28. This construction affords means whereby the side walls 34 may be moved inwardly or outwardly to adapt the hopper to receive a stack of sheets (not shown) of various sizes and retain said sheets in substantial alignment. Sheets are arranged in the hopper 27 flat against the back wall 28 with their lower aligned edges resting upon the bottom wall 29.

The sheets in the stack may be individual sheets or manifold sheets of the kind commonly used in connection with the operation of business machines, and they are adapted to be selectively and individually withdrawn from the hopper and discharged in a position for ready insertion into a typewriter or other business machine. To this end, novel means is provided in the present machine for positively engaging the topmost or foremost sheet of the stack at selected intervals and withdrawing said sheet from the stack into a position clear of the bottom wall 29, whereupon said sheet is released automatically and discharged.

The sheet feeding mechanism, generally, includes a pivotally mounted substantially U-shaped lever 41, having its upwardly extending arms 42 arranged within end walls 43 provided on the hopper 27. As best shown in Figs. 1 and 5, the end walls 43 may be sheet metal stampings

provided with inwardly disposed marginal flanges 44 within the confines of which the lever 41 operates. The flanges 44 on the upper ends of the end walls 43 overlie the end edges of a rearwardly extending top wall portion 45 of the hopper back wall 28 and may be suitably secured thereto, as by welding. Additional rigidity is afforded by riveting or otherwise securing end flanges 45a (Fig. 5) of the hopper back wall 28 to said end walls so as to provide a substantially one-piece structure.

The upwardly disposed free end portions of the lever arms 42 are pivoted, as at 46, to the end walls 43, and the bight portion 47 of said lever is disposed closely adjacent to the hopper bottom wall 29. In operation, the lever is adapted to have reciprocal rotation about its pivots 46 so as to carry the bight portion 47 toward and away from a stack of sheets arranged in the hopper. Movement of the lever may be best obtained by providing manually actuatable means, generally indicated at 48 in Fig. 1, which means may include a mounting plate 49 and a manually actuatable bell-crank lever 51 pivoted to said plate at 52. One arm 53 of said lever is connected to the wire 54 of a "Bowden" cable 55, the other end of which carries a plunger 56.

Referring now to the disclosure in Fig. 5, it will be observed that the plunger 56 is positioned in alignment with and below a crossbar 57 firmly secured by screws 58 to rearwardly extending end portions 59 of the lever side arms 42. Such positioning of the plunger may be retained by the provision of a bracket 60 on the rear face of the plate 32. This bracket may be secured to the plate 32 as by means of screws 61, access to which may be obtained through screw driver openings 62 in the hopper back wall 28. It will thus be observed that the channel 31 in the hopper back wall affords suitable clearance for the heads of screws 61. The bracket 60 includes a clamp plate, indicated at 63, which affords means to receive and firmly secure the adjacent end of the "Bowden" cable 55 in place.

Tension springs 64 (only one shown in Fig. 5) are connected at one end 65 to the hopper back wall 28 and at their other ends 66, one to each of the rearwardly extending end portions 59 of the U-shaped lever arms 42. These springs normally hold the U-shaped lever 41 in the position illustrated in broken lines in Fig. 5. It should be quite evident that, when the manually actuatable member 48 is operated to raise the plunger 56, the lever 41 moves, against the action of spring 64, inwardly toward a stack of sheets in the hopper. The U-shaped lever 41 carries suitable sheet penetrating and gripping means on its bight portion 47 to coact with the foremost sheet in the stack so as to engage said sheet and carry it away from the stack into a position of discharge. Such means is best illustrated in Figs. 5 through 10.

As shown in Figs. 5 through 10, the bight portion 47 of the lever 41 is provided on its under face substantially midway between its arms 42 with a plate or strap member 67. This strap member has its medial portion offset downwardly to provide a channel 68 and its end portions 69, which lie against the bottom face of the bight portion, are secured thereto as by means of digital screws 71. Upon referring to Fig. 6, it will be observed that the screws 71 are threaded into the end portions 69 of the strap 67 and extend upwardly through slotted openings 72 in the bight portion 47 so as to afford means whereby the

strap member 67 may be adjusted transversely relative to the bight portion. A projection or extension 73 is provided on one edge of the downwardly offset medial portion of the strap member 67. This extension is turned downwardly and is suitably recessed or notched on its free edge, as at 74, for a purpose to be explained hereinafter.

A slide 75, also fashioned from strap stock, is extended through and is slidable within the channel 68. The rearwardly disposed projecting end portion of said slide is turned downwardly, as at 76, and is suitably apertured at 77 for a purpose to be described hereinafter. The other or forward end of the strap slide 75 is bent downwardly angularly outwardly to define a lip 79, and then inwardly angularly. A horizontally disposed slot 81 is provided inwardly of the free end of the portion 79. The intermediate portion of the slide 75, which lies within the channel 68, is longitudinally slotted at 82 to freely receive the end of a thumb screw 83.

The thumb screw 83 is carried in a bifurcated slide block 84 disposed beneath the strap 67 and which affords a mounting for a pair of spring fingers 85. These spring fingers 85 preferably are formed of a single piece of spring steel wire coiled at least once about the thumb screw 83. The strap 67 is suitably slotted at 86 for free passage of the thumb screw 83. This assembly is such that the slots 82 and 86 serve to guide the block 84 for adjustment toward or away from the downturned strap portion 73.

The two extremities of the spring fingers 85 project freely through the recess 74 in the end of the downturned stationary strap extension 73 and through the slot 81 in the front lip 79 of the slide 75. Means is provided whereby the spring fingers 85 and their mounting may be adjusted as aforesaid so as to vary the extent of projection of the free end portions or jaws 88 of said fingers through and beyond the front lip 79. To this end, a screw threaded stem 78 is secured at one end in the block 84. This stem extends rearwardly and is threaded into a digital member or adjusting knob 89 securely mounted for free rotation in the aperture 77. A spring washer 91, interposed between the downturned portion 76 of the slide 75 and a shoulder on the adjusting knob 89, affords friction means to resist free turning of said knob. When adjustment of the spring fingers 85 is required, the adjusting knob 89 is rotated in the desired direction to move the block 84 toward or away from the front end of the slide.

In operation, the manually actuatable lever 51 is depressed, whereupon the U-shaped lever 41 is carried forwardly, toward the stack of sheets in the hopper 27, initially a distance sufficient to place the projecting jaws 88 of the spring fingers 85 in surface contact with the foremost sheet on the stack. When this occurs, sufficient resistance is offered to continued movement forwardly of the slide 75 and fingers 85 carried thereby to retard continued forward motion thereof during continued forward swinging of the lever, whereupon the slide 75 is shifted rearwardly in the channel 68. During such sliding of the slide 75 the downturned flange 73 of the strap 67 advances relative to the fingers and, because of the restricted width of the recess 74 therein, the side edges 74a of said recess engage and draw the spring fingers together so as to thereby cause their pointed ends or jaws 88 to penetrate the first sheet in the stack and grip said sheet firmly.

When the forward cycle of operation of the lever 41 is completed, the manually actuatable lever 51 is released and the springs 64 return to U-shaped lever 41 to its initial or starting position (illustrated in broken lines in Fig. 5). During this return movement, the foremost sheet is lifted off the stack and its lower edge is carried beyond the edge of the hopper bottom wall 29 into a position above the hopper discharge opening indicated generally at 92. However, because the sheet is still firmly gripped by the spring fingers 88, it is not released and discharged at this time.

Means to release the sheet from the fingers 15 just prior to the completion of the return stroke of the U-shaped lever 41 is accomplished by providing suitable stripper means. As illustrated, such means may comprise a transversely extending sheet metal housing 93 secured at its ends 20 to the end walls 43. A substantially vertical wall 94 of said housing is suitably apertured, as at 95, and slotted at its ends, as at 96, so as to permit free passage of the bight portion 47 and the sheet gripping mechanism into the interior 25 of said housing. Obviously, the engaged sheet cannot enter the housing 93, hence movement of the pointed ends 88 of the spring fingers 85 inwardly beyond the face of the housing wall 94 will constitute said wall stripping means. 30 Accordingly, the sheet is forcibly withdrawn from the spring fingers and dropped by gravity through the discharge opening 92. It may then be guided by means of an adjustable guide plate 97 into position within a typewriter or other business machine.

The housing 93 is provided on its forward wall 98 with an aperture 99, suitably fitted with a resilient washer 101. This aperture is in alignment with and receives the digital member 89 40 therethrough when the sheet gripping means is wholly disposed within the housing 93. This affords means whereby the digital member 89 may be manually engaged for adjusting the relative position of the spring fingers and slide. The resilient washer 101 also constitutes abutment 45 means for the slide 75 to limit its movement in a direction away from the stack during the operation of the lever 41.

As will be best observed in Fig. 5, the downwardly turned end portion 76 of the slide 75 initially strikes against the resilient washer 101, thereby retarding further movement of said slide. However, since the lever 41 has not, at this time, reached the limit of its movement in that direction, 55 said lever continues to move into the housing, thus causing the slide 75 to be shifted forwardly relative to the channel 68. Such forward or return shifting of the slide 75 carries the walls 74a of recess 74 out of engagement with the spring fingers 85 and permits said fingers to again return to their spread-apart condition. The spreading of the fingers insures release of the sheet in the event it had not been stripped just prior to such spreading. The mechanism is now reset to repeat its operating cycle in the manner described hereinbefore.

There may be occasions when the stack of sheets is of a size or width greater than the height of the hopper back wall 28. Should such sheets or stack of sheets extend a material distance above the top edge of said back wall, there is a possibility of the stack's becoming misplaced to such an extent as to impair the operation of the sheet gripping mechanism. Accordingly, means is provided whereby the project-

ing upper portion of a stack of sheets may be suitably supported. To this end, the back wall 28 of the hopper is provided with a pair of vertically adjustable slides 102, which are freely slideable in guides 103 formed in said back wall so as to be adjusted vertically to any desired height within the capacity of said slides.

Although an exemplary form of the present invention has been fully disclosed in the accompanying drawings, and described in detail in the foregoing specification, it should be understood that the sheet feeding machine as a whole and the sheet gripping mechanism specifically may embody a wide variety of modifications in detail construction without departing from the spirit of the invention or the scope of the appended claims.

I claim:

1. A sheet gripping device for use in a sheet feeding machine, a lever swingable toward and away from a stack of sheets in said machine, a channeled member on said lever, a slide in the channel, a pair of normally spaced apart spring fingers carried by said slide, and means on the channeled member cooperatively associated with the fingers to move the fingers toward each other when the slide is moved in one direction relative to said channeled member.

2. A sheet gripping element comprising a support, a channeled member on said support, a slide in the channel, a pair of spaced spring fingers carried by and movable with said slide, and relatively stationary means engageable by said fingers when the slide is moved in one direction relative to said channeled member to urge the fingers toward each other.

3. A sheet gripping element comprising a support, a channeled member on said support, said member being adjustable relative to the support, a slide in the channel, a pair of spaced spring fingers carried by and movable with said slide, and relatively stationary means engageable by said fingers when the slide is moved in one direction relative to said channeled member to urge the fingers toward each other.

4. A sheet gripping element comprising a support, a channeled member on said support, a slide in the channel, a pair of spaced spring fingers carried by and movable with said slide, means to adjust said fingers on said slide, and relatively stationary means engageable by said fingers when the slide is moved in one direction relative to said channeled member to urge the fingers toward each other.

5. A sheet gripping element comprising a support, a channeled member on said support, said member being adjustable relative to the support, a slide in the channel, a pair of spaced spring fingers carried by and movable with said slide, means to adjust said fingers on said slide, and relatively stationary means engageable by said fingers when the slide is moved in one direction relative to said channeled member to urge the fingers toward each other.

6. A sheet gripping device for use with a sheet feeding machine wherein a stack of sheets is supported edgewise in a vertically inclined hopper, a spring tensioned U-shaped lever pivotally mounted on said frame, a strap secured medially of the bight portion of the lever, said strap being offset to provide a channel, a member slidable in the channel, spaced sheet piercing and gripping fingers carried by and movable with said slidable member, said strap including means movable relative to the fingers for

contracting their ends to pierce and grip a sheet contacted thereby, and means to enable said fingers to release the sheet.

7. The structure recited in claim 6 and in which the fingers are adjustable relative to the slide member.

8. A sheet feeding machine comprising, in combination, an adjustable standard, a bracket attached to one end of said standard for attaching the standard to a support, a frame adjustable on the other standard end, a hopper for a stack of sheets on said frame, said hopper being disposed substantially vertically to support the stack edgewise, a U-shaped lever mounted on said hopper for swinging movement toward and away from said stack, spring means normally retaining the lever spaced from the stack, manually actuatable means to move the lever toward said stack, means on said lever adapted to penetrate and grip the top sheet of the stack and withdraw said sheet from the stack during one cycle of lever movement, and means in said frame to strip the sheet from the gripping means when the lever returns to its normal rest position.

9. A sheet feeding machine comprising, in combination, an adjustable standard, a bracket attached to one end of said standard for attaching the standard to a support, a frame adjustable on the other standard end, a hopper for a stack of sheets on said frame, said hopper being disposed substantially vertically to support the stack edgewise, a U-shaped lever mounted on said hopper for swinging movement toward and away from said stack, spring means normally retaining the lever spaced from the stack, manually actuatable means to move the lever toward said stack, means of said lever adapted to penetrate and grip the top sheet of the stack and withdraw said sheet from the stack during one cycle of lever movement, means in said frame to strip the sheet from the gripping means when the lever returns to its normal rest position, and a guide chute into which the released sheet is discharged.

10. In a sheet feeding machine, a hopper, means for withdrawing successive sheets from a stack of sheets in said hopper, said means comprising a U-shaped member having the ends of its leg portions pivotally mounted on the hopper, slidable means on the bight portion of the lever, a pair of spring fingers carried by said slidable means adapted to penetrate and grip the leading sheet between the ends of said fingers upon contacting engagement with said sheet when the lever is rocked toward said stack, and means engageable by the slidable means when the lever is rocked away from the stack to spread the fingers.

11. In a sheet feeding machine comprising an open faced hopper adapted to contain a substantially vertically disposed stack of sheets, means for withdrawing individual sheets from the face of said stack, said means including picker fingers operative to grip the individual sheet when carried into piercing contact with said sheet, and fixed means effective when the sheet has been withdrawn from the hopper to release the picker fingers from the sheet.

12. In a sheet feeding machine comprising an open faced hopper adapted to contain a substantially vertically disposed stack of sheets, reciprocal means for withdrawing individual sheets from the face of said stack, said means including slidable picker fingers operative to grip the individual

sheet when carried into piercing contact with said sheet, and fixed means effective when the sheet has been withdrawn from the hopper to release the picker fingers from the sheet.

13. A sheet-feeding machine comprising, in combination, an adjustable standard, a frame on said standard, a hopper for a stack of sheets on said frame, a U-shaped lever mounted on said hopper for swinging movement toward and away from said stack, a sheet-gripping element including a channelled member on said U-shaped lever, a slide in the channel, normally spaced-apart spring fingers carried by said slide and means on the channelled member cooperatively associated with the fingers to move the fingers toward each other when the slide is moved in one direction relative to said channelled member.

14. A sheet-feeding machine comprising, in combination, a frame, a hopper for a stack of sheets on said frame, a lever mounted on said hopper for swinging movement toward and away from said stack, a sheet-gripping element including a channelled member on said U-shaped lever, a slide in the channel, normally spaced-apart spring fingers carried by said slide, and means on the channelled member cooperatively associated with the fingers to move the fingers toward each other when the slide is moved in one direction relative to said channelled member.

15. The structure recited in claim 14, having means to adjust said spring fingers for a desired depth of penetration into said stack.

16. In a sheet feeding machine, means movable toward and away from a stack of sheets to withdraw the leading sheet therefrom, said means including a reciprocal lever and means to move the lever, a slideable member on said lever, spaced spring fingers on said slideable member adapted to contact the leading sheet when the lever is swung toward said stack, said lever continuing its movement independently of the slideable member toward the stack after the sheet has been contacted, means on the lever to coact with and contract the fingers so as to penetrate and grip the sheet between the fingers during such lever movement, and means engageable by the slideable member to release the sheet when the lever reaches the limit of its movement away from the stack.

17. In a sheet feeding machine, means movable toward and away from a stack of sheets to withdraw the leading sheet therefrom, said means including a reciprocal lever and means to move the lever, a slideable member on said lever, spaced spring fingers on said slideable member adapted to contact the leading sheet when the lever is swung toward said stack, said lever continuing its movement independently of the slideable member toward the stack after the sheet has been contacted, means to coact with and contract the fingers so as to grip the sheet between the fingers during such lever movement, and means engageable by the slideable member to release the sheet when the lever reaches the limit of its movement away from the stack.

18. In a sheet feeding machine, means movable toward and away from a stack of sheets to withdraw the leading sheet therefrom, said means including a reciprocal lever and means to move the lever, a slideable member on said lever, spaced spring fingers on said slideable member adapted to contact the leading sheet when the lever is swung toward said stack, said lever continuing its movement independently of the slideable member toward the stack after the sheet has been contacted, means to coact with and contract the fingers so as to grip the sheet between the fingers during such lever movement, and means to release the sheet when the lever reaches the limit of its movement away from the stack.
